UNITED STATES PATENT OFFICE.

CARL E. YOUNGBERG, OF SEATTLE, WASHINGTON.

CARDBOARD FIGURE.

Application filed February 27, 1922. Serial No. 539,658.

To all whom it may concern:

Be it known that I, CARL E. YOUNGBERG, a citizen of the United States, residing at Seattle, in the county of King and State of Washington, have invented certain new and useful Improvements in Cardboard Figures; and I do hereby declare the following to be a full, clear, and exact description of the invention, such as will enable others skilled in the art to which it appertains to make and use the same.

This invention relates to a figure made of plain sheet material and the method of making the same which figure is to be used as a toy figure or for an advertising device or for both purposes.

It is an object of this invention to construct figures of various designs from a single integral sheet of cardboard having various portions and to provide locking means from said integral sheet to hold the various portions in proper and desired positions.

It is a further object of this invention to provide such a figure having a body and head portion disposed in a plane normal to that in which the figure faces and having leg portions for supporting the body and head portion disposed in vertical planes or planes slightly inclined to the vertical and also to provide means for holding said portions in proper positions. These and other objects and advantages of the invention will be fully set forth in the following description made in connection with the accompanying drawings in which like reference characters refer to the same parts throughout the different views and, in which—

Fig. 1 is a view in front elevation of the device;

Fig. 2 is a view in side elevation as seen from the right of Fig. 1;

Fig. 3 is a view in rear elevation of the device;

Fig. 4 is a view of the blank for forming the device after the same is cut from the sheet of material;

Fig. 5 is a view in front elevation of a modified form of the device;

Figs. 6 and 7 are, respectively, views in side elevation and rear elevation of such modified form; and

Fig. 8 is a view of a sheet of material having the blank for the device indicated thereon.

Referring to the drawings, and particularly Figs. 1 to 4, the device is seen to comprise a figure made of flat material such as cardboard and having a body portion 1 comprising a representation of head, body and arms, which portion is disposed in a plane slightly inclined to the vertical and which is substantially normal to the direction in which the figure faces. The device also comprises leg portions 2 disposed in different planes from the portion 1 which planes are vertical or slightly inclined to the vertical and substantially parallel to the direction in which the figure faces. The leg portions 2 have projecting from and bent downwardly from their rear edges tabs 3 extending laterally beyond the portions 2 and provided with short slits adapted to engage the rear edges of said leg portions to hold the same in proper and desired spaced relation. A holding tongue 4 projects from the rear edge of the leg portions or the connecting strip between said portions and is extended upwardly to pass through a slit 1^a formed in the body portion and hold said body portion in firm and desired position.

The blank before being bent is shown in Fig. 4 and the various portions described are indicated in said figure. It will be seen that the body portion, the leg portions and the tabs or holding portions 3 and 4 converge or merge into a common area or portion of the blank. The lines along which the body, leg and holding portions can be bent are indicated by the dotted lines 5.

In Figs. 5, 6 and 7, a slightly modified form of the device is shown having the body portion 6 comprising the arm 6^a and having the leg portions 7. The body portion 6 and the leg portions 7 extend in similar planes to the portions 1 and 2 already described. The tabs 8 project upwardly from the rear top portion of the legs 7 and are held in properly spaced relation by engaging with the edges of tabs 9 projecting at each side of a tongue 10 which is bent upwardly from the rear edge of the portion connecting the legs 7 and extends upwardly to and through a slit 6^b formed centrally on the body portion 6. The legs 7 are thus held in properly spaced position by the tabs 8 and 9 and the body is held in proper and desired position by the tongue 10. It will, of course, be understood that the tongues 4

and 10 described engage the sides of the slits 1^a and 6^b, respectively, and are frictionally held therein.

In Fig. 8 a sheet of material 11 is shown having indicated thereon a blank from which a figure is to be made. This particular form of figure is similar to that shown in Figs. 1 to 3 but the structure of the holding means or tabs is the same as that shown in Figs. 6 and 7 and the parts are designated similar to the parts in the latter figures. A legend also appears on the sheet 11 constituting instructions for forming the figure. The sheet 11 may be any desired sheet of material or, if desired, may be made in the shape and size of a postcard so that the same can be sent through the mail.

The device described has been found to have great utility both as a toy and as an advertising device for advertising certain well known brands of goods. The device can be inexpensively made and easily and quickly cut out and folded to the desired position.

It will, of course, be understood that various changes in the form, details and arrangement of the various parts of the device can be made without departing from the scope of applicant's invention which, generally stated, consists in the matter shown and described and set forth in the appended claims.

What is claimed is:

1. A figure made of flat sheet material comprising a single integral piece of said material and comprising a body portion disposed substantially in one plane, leg portions disposed in planes extending at an angle to that of said body portion, adapted to contact a support and support said body portion and means engaging said body portion and legs for holding said legs in properly spaced positions.

2. A figure formed of a single integral piece of sheet material and comprising a body portion, leg portions extending in planes substantially normal to that of the body portion adapted to contact a support and support said body portion and means extending from said body portion to said leg portions for holding said body portion in desired position.

3. A figure comprising a body and head portion formed of one thickness of flat material disposed in a plane which is substantially normal to the direction in which the figure faces, leg portions each formed of one thickness of flat material disposed in planes slightly inclined to the vertical and substantially parallel to the direction in which the figure faces and tabs engaging said leg portions for holding the same in properly spaced relation, said portions and tabs being integrally connected.

4. The structure set forth in claim 3, said

tab portions extending in planes substantially normal to the plane of said leg portions.

5. A figure comprising a body portion formed of one thickness of flat material disposed in a plane substantially normal to the direction in which the figure faces, leg portions each formed of one thickness of flat material disposed in planes substantially parallel to the direction in which the figure faces and adapted to support said body portion and a tongue extending from said leg portion and frictionally engaging said body portion to hold the same in desired position.

6. A toy figure made from a single blank of sheet material comprising body, leg and holding portions, the body portion being folded into a plane extending substantially at right angles to the plane into which said leg portions are folded, one of said holding portions being adapted to engage said legs and another extending from said legs and engaging said body portion to hold the parts in proper position.

7. A toy figure made from a single blank of sheet material having a body portion disposed in a plane substantially normal to the direction in which the figure faces, said body portion being folded along a straight line, and leg portions folded along straight lines in planes substantially normal to that of said body portion, and holding means engaging each leg to hold the same in proper position, and a central holding means extending from the legs to and engaging said body portion to hold the latter in proper position.

8. A step product comprising a flat blank having a body and head portion at one end thereof, leg portions having their longitudinal center lines projecting oppositely at the sides of the blank, and holding portions for the body and leg portions at the other end thereof, all of said portions being united in a common central portion and having lines thereon indicating where said portions are to be folded to form an upright figure adapted to stand on said leg portions.

9. A step product comprising a sheet of flat material having thereon the representation of a figure comprising a body portion at one end thereof, leg portions at each side of said blank and having their longitudinal center lines substantially normal to that of said body portion, and holding portions for the body and leg portions at the other end thereof, all merging or united in a common central portion, lines indicating where said portions may be folded when cut from said sheet to form an upright figure supported by said leg portions.

10. A figure made of a flat piece of material and having an upper body portion disposed in one plane inclined slightly rear-

wardly from the vertical, flat leg portions below said body portion, and substantially in the rear thereof disposed in planes substantially normal to the plane of the body portion, and tabs adapted to frictionally engage the body and legs to hold the same in fixed position, said body and leg portions and tabs all being connected as integral parts of said flat piece of material.

10 11. A step product comprising a flat blank having a body portion at one end with the head portion thereof forming an end termi-

nal of said body portion, leg forming portions projecting at each side of said blank and of the longitudinal center line of said body portion and a strip projecting at the end of said blank opposite said body portion, said body portion having a slit therein adapted to receive said strip and said blank having a central common portion connecting all of said portions and strip.

In testimony whereof I affix my signature.

CARL E. YOUNGBERG.
